United States Patent Office

Des. 206,270
Patented Nov. 22, 1966

206,270

TIE HOLDER

Walter A. Dunn, 139 Baker St., Warwick, R.I. 02886

Filed Nov. 22, 1965, Ser. No. 88,255

Term of patent 14 years

(Cl. D33—8)

FIG. 1

FIG. 2

FIG. 3

FIG. 4

FIG. 1 is a perspective view of a tie holder showing my new design;

FIG. 2 is a top plan view thereof;

FIG. 3 is an end elevational view thereof; and

FIG. 4 is a rear elevational view thereof.

I claim:

The ornamental design for a tie holder, substantially as shown.
